HIGH-FREQUENCY ELECTRIC DISCHARGE
DEVICEDonald A. Wilbur, Troy, and Louis D. Roberts,
Schenectady, N. Y., assignors to General Elec-
tric Company, a corporation of New York

Application December 11, 1944, Serial No. 567,556

14 Claims. (Cl. 250—27.5)

1

Our invention relates to high frequency electric discharge devices and more particularly to improved high frequency devices of the magnetron type.

Magnetrons of the split-anode type have been employed as oscillators in the moderately high frequency range, for example, from 1 to 400 megacycles. When operating in the lower portion of this frequency range, the power handled by the device has been quite limited due to heating and destruction of the seals between the high frequency conductors associated with the anode segments and the enclosing envelope or with destruction of other portions of the envelope. We have found that the power handled by devices of this character may be materially increased if electrons from the interelectrode space are prevented from bombarding the region of the seals about the high frequency lead-in conductors. In accordance with the teachings of our invention, we provide an improved magnetron construction in which the escape of electrons from the interelectrode space is minimized and in which the escaping electrons are prevented from reaching the seals about the high frequency lead-in conductors.

It is an object of our invention to provide a new and improved electric discharge device of the magnetron type.

It is another object of our invention to provide a new and improved magnetron construction in which bombardment of the seals about the high frequency conductors is effectively eliminated.

In one illustrated embodiment of our invention, a magnetron device of the split-anode type is provided with shields mounted on the anode members and arranged with respect to the gaps between the anode members so that any electrons escaping from the interelectrode space through the gaps must travel in a zigzag path. This minimizes the escape of electrons during the portion of the high frequency cycle that the high frequency voltage is lower than the cutoff voltage of the gaps of the device. In order to protect the seals from the electrons which do escape from the interelectrode space, annular disks or shields of molybdenum, or other material which is a poor secondary emitter, are supported in insulated relation about the high frequency lead-in conductors. These shields become electrostatically charged due to the collection of electrons thereon and are effective to force the remaining electrons which have escaped from the interelectrode space and are traveling towards the region of the seals to be collected on the high frequency conductors.

In accordance with another illustrated embodiment of our invention, we provide a shielding enclosure in the form of a rectangular box which totally encloses the interelectrode space of the

2

device. The walls of the box are provided with openings through which the anode members and the cathode may pass in spaced relation with respect to the walls of the openings. The enclosure is supported in insulated relation with respect to the electrodes so that the shield may become negatively charged as electrons are collected.

For a better understanding of our invention, reference may be had to the following description taken in connection with the accompanying drawing in which Fig. 1 is a perspective view of one embodiment of our invention; Fig. 2 is a detailed view showing the construction of one of the shields secured to the high frequency lead-in conductors, and Fig. 3 is a perspective view of a modification of our invention.

Referring now to Fig. 1 of the drawing, we have shown our invention embodied in a magnetron device including a generally cylindrical evacuated envelope 1 preferably formed of glass. The envelope encloses an anode structure comprising two anode members 2 and 3 having semi-cylindrical faces arranged in opposed relation to provide a circular array. As illustrated in the drawing, the members 2 and 3 are mounted in mutually spaced relation to provide gaps 4 and 5 between them and are, respectively, supported by parallel conductors 6 and 7 which extend through one end of the envelope. The conductors 6 and 7 may to advantage be formed of copper tubing and are sealed through the end wall of the envelope 1 by suitable seal constructions which may include a fernico shoulder or sleeve 8.

A source of electrons in the generally annular space defined by opposed ends of members 2 and 3 is provided by an elongated cathode 9 which may be a tungsten wire, either uncoated or coated with a suitable electron emissive oxide. The cathode is supported symmetrically between the curved surfaces of anode members 2 and 3 by lead-in conductors 10 and 11 which are sealed through the base of the envelope 1 to provide externally accessible terminals 12 (only one of which is visible on the drawing) for a source of heating current. One of the terminals may also be connected to a source of high negative direct current voltage if the anode is to be operated at ground potential. Suitable end plates or shields 13 are mounted opposite the open ends of the interelectrode space to minimize the escape of electrons, and these shields may each be supported from one of the cathode lead-in conductors, such as conductor 10, by a wire bracket 14. A metallic tab 15 carrying a suitable getter material may also be supported in the envelope by a wire 16 supported from the lead-in conductor 10.

During the portion of the high frequency voltage cycle that the voltage is less than the cutoff voltage of the gaps of the device electrons have

a tendency to escape from the gaps between the opposed ends of the anode members 2 and 3. To minimize the escape of these electrons, we provide shield members 17, 18, 19 and 20 supported from the anode members 2 and 3 and arranged to require any electrons escaping from the gaps 4 and 5 to travel in a circuitous or zigzag path. As illustrated, the shield members are formed of material which is a poor secondary emitter and may be of sheet metal of good electrical conductivity which is bent into angular or L shape. One shield is supported from each side of each of the anode members with the end portions extending into the region of the gaps. For example, shield members 17 and 20 extend over the gaps 4 and 5, respectively, while the shield members 18 and 19 are spaced further from the surfaces of the anode members and have the end portions thereof in alignment with or in overlapping relation with the end portions of the shields 17 and 20, thus requiring the electrons escaping from gaps 4 and 5 to travel in a zigzag path and greatly increasing the likelihood that the electrons will be collected.

In order to prevent electrons escaping from the interelectrode space from bombarding the seals between envelope 1 and conductors 6 and 7, we provide on the conductors 6 and 7 between the anode members 2 and 3 and the seals with the envelope 1 suitable shields in the form of metallic disks 21. As is best illustrated in Fig. 2, the disk 21 is supported on the upper end of an insulating cylinder 22 which is supported on the conductor 6 in any suitable manner. As illustrated, the cylinder is supported by a wire bracket 23 having one portion secured to the conductor 6 and another portion engaging the cylinder 22. In a similar manner, disk 21 is secured in position on the upper end of the cylinder 22 by a wire bracket 24 having one or more struts 25 secured to the shield 21. The shield on conductor 7 is of the same construction. During operation of the device, the disks 21 become charged negatively by the collection of electrons and are effective to compel electrons which escape from the interelectrode space to move to conductors 6 and 7 and be collected.

For the sake of simplicity, the source of magnetomotive force which is impressed across the anode of the device in a direction parallel to the elongated cathode 9, as indicated by the arrow in Fig. 1, has not been illustrated. It will also be understood that the frequency of operation of the device is determined by a short circuiting conductor which is usually mounted for movable engagement with the high frequency conductors 6 and 7.

In the operation of the illustrated embodiment of our invention, electrons emitted from the cathode 9 travel in a curvilinear path in the interelectrode space under the action of the resultant action of an electric field resulting from a direct current voltage impressed between the cathode and the anode members and a magnetic field produced in the interelectrode space in a direction parallel to the elongated cathode member. Electrons tend to escape from the gaps 4 and 5 during that portion of the high frequency cycle that the high frequency voltage is less than the cutoff voltage of the gaps of the device. The cutoff voltage may be reduced by reducing the width of the gaps, but at the expense of increasing the capacity between the anode members. In the arrangement of our invention illustrated, the shield members 17 to 20, inclusive, require the

electrons escaping from the gaps to travel a circuitous path to minimize the number of escaping electrons without appreciably increasing the capacity between the anode members which would result from the reduction in the width of the gaps 4 and 5. The reduction in gap width also decreases efficiency and has a detrimental effect on certain electrical characteristics such as the loading characteristics. The metal shield members 21 which surround the high frequency leads 6 and 7 are formed of material which is a poor secondary emitter to prevent the liberation of secondary electrons. These shield members, as previously stated, become electrostatically charged during operation of the device by the collection of some electrons and operate to force other electrons to be collected by conductors 6 and 7 which would otherwise bombard the seals between the high frequency conductors 6 and 7 and the envelope 1.

It is a characteristic of shield members employed in accordance with our invention that they have an extended area in a plane perpendicular or at least at a substantial angle with the direction of the magnetic field of the device.

The modification of our invention illustrated in Fig. 3 is in general similar to the modification of Fig. 1, and the same reference numerals have been used to designate corresponding parts. It will be noted that the relative dimensions of the parts in the arrangement of Fig. 3 are different, resulting from the different shielding arrangement employed. For example, the envelope 1 is considerably shorter than the envelope of Fig. 1 and the parallel conductors supporting the anode members are considerably shorter. This improves the operation of the device with respect to the magnitude of the frequencies attainable.

Referring now to Fig. 3, the interelectrode space defined by the elongated cathode 9 and the opposed surfaces of the anode members 2 and 3 is substantially totally enclosed by a box-like structure 26. As illustrated in the drawing, this structure is substantially rectangular and has openings 27 centrally located in opposite walls to receive the cathode 9. The walls of the enclosure surrounding the anode members 2 and 3 are also provided with apertures 28 which are slightly larger than the cross section of the anode members so that there is no electrical contact between the shield and the members. The enclosure 26 is supported in the desired relationship with respect to the electrode assembly and in insulated relation with respect thereto by supporting wires 29 and 30 which are secured, respectively, to the lead-in conductor 10 and a wall of the enclosure 26. The conductors 29 and 30 are mechanically joined in electrically insulated relation by a glass bead 31. A sheet metal spring member 32 for tensioning the cathode 9 is also visible in Fig. 3.

The operation of the embodiment illustrated in Fig. 3 is believed to be apparent from the detailed description of the operation of the embodiment illustrated in Fig. 1. The total enclosure provided in Fig. 3 practically precludes any electrons which escape from the interelectrode space from bombarding any portion of the envelope and in this way materially increases the power obtainable from a device of given dimensions.

With magnetron constructions including the structural features of the illustrated embodiments of our invention, we have been able to operate at considerably higher power requirements without experiencing any difficulty from destruc-

tion of the seals about the high frequency conductors or any other portion of the envelope.

While we have shown and described particular embodiments of our invention, it will be obvious to those skilled in the art that changes and modifications may be made without departing from our invention in its broader aspects, and we, therefore, aim in the appended claims to cover all such changes and modifications as fall within the true spirit and scope of our invention.

What we claim as new and desire to secure by Letters Patent of the United States, is:

1. A magnetron device adapted to have high power output comprising an envelope, a source of electrons, an anode structure within said envelope adjacent said source of electrons including mutually spaced anode members having opposed surfaces and defining between said surfaces a space charge chamber within which electrons constituting the space charge of the device are adapted to move, said anode members also defining between said surfaces gaps located on the periphery of said space charge chamber, shield members substantially completely covering said gaps to force electrons escaping from said gaps to travel a circuitous path, lead-in conductors sealed through said envelope and connected with said anode members, and means including a metallic shielding structure supported in insulated relation with respect to said anode structure in the path of electrons traveling from said gaps to the region of the seals between said envelope and said conductors to force collection of electrons escaping from said gaps on said lead-in conductors and thereby to prevent electrons from bombarding the seals between said conductors and said envelope.

2. A magnetron device adapted to have high power output comprising an envelope, a source of electrons, an anode structure within said envelope adjacent said source of electrons including mutually spaced anode members having opposed surfaces and defining between said surfaces a space charge chamber within which electrons constituting the space charge of the device are adapted to move, said anode members also defining between said surfaces gaps located on the periphery of said space charge chamber, shield members substantially completely covering said gaps to force electrons escaping from said gaps to travel a circuitous path, lead-in conductors sealed through said envelope and connected with said anode members, and means including a metallic shielding structure surrounding each of said lead-in conductors and supported in insulating relation with respect thereto in the path of electrons traveling from said gaps to the region of the seals between said envelope and said conductors to force collection of electrons escaping from said gap on said lead-in conductors and thereby to prevent electrons from bombarding the seals between said conductors and said envelope.

3. A magnetron device adapted to have high power output comprising an envelope, a source of electrons, an anode structure within said envelope adjacent said source of electrons including a pair of mutually spaced anode members having opposed surfaces and defining between said surfaces a cylindrical space charge chamber within which electrons constituting the space charge of the device are adapted to move, said anode members also defining between said surfaces gaps located on diametrically opposite sides of said cylindrical space charge chamber, shielding means for mini-

mizing the escape of electrons from said gaps including a pair of angular members of conducting material substantially completely covering each of said gaps, each of said angular members in each said pair being supported from a different one of said anode members and having a portion extending toward the other of said angular members in overlapping relationship therewith over one of said gaps whereby said angular members cooperate with the anode structure to collect electrons passing through said one of said gaps, lead-in conductors sealed through said envelope and connected with said anode members, and means including a metallic shielding structure supported in insulated relation with respect to said anode structure in the path of electrons traveling from said gaps to the region of the seals between said envelope and said conductors to force collection of electrons escaping from said gaps on said lead-in conductors and thereby to prevent electrons from bombarding the seals between said conductors and said envelope.

4. A magnetron device adapted to have high power output comprising an envelope, a source of electrons, an anode structure within said envelope adjacent said source of electrons including a pair of mutually spaced anode members having opposed surfaces and defining between said surfaces a cylindrical space charge chamber within which electrons constituting the space charge of the device are adapted to move, said anode members also defining between said surfaces gaps located on diametrically opposite sides of said cylindrical space charge chamber, shielding means for minimizing the escape of electrons from said gaps including a pair of angular members of conducting material substantially completely covering each of said gaps, each of said angular members in each said pair being supported from a different one of said anode members and having a portion extending toward the other of said angular members in overlapping relationship therewith over one of said gaps whereby said angular members cooperate with the anode structure to collect electrons passing through said one of said gaps, lead-in conductors sealed through said envelope and connected with said anode members, and means including a metallic shielding structure surrounding each of said lead-in conductors and supported in insulated relation with respect thereto in the path of electrons traveling from said gaps to the region of the seals between said envelope and said conductors to force collection of electrons escaping from said gaps on said lead-in conductors and thereby to prevent electrons from bombarding the seals between said conductors and said envelope.

5. A magnetron device adapted to have high power output comprising an envelope, a source of electrons, an anode structure within said envelope adjacent said source of electrons, including mutually spaced anode members having opposed surfaces and defining between said surfaces a space charge chamber within which electrons constituting the space charge of the device are adapted to move, said anode members also defining between said surfaces gaps located on the periphery of said space charge chamber, lead-in conductors sealed through said envelope and connected with said anode members, and means including a metallic shielding structure supported in insulated relation with respect to said anode structure in the path of electrons traveling from said gaps to the region of the seals between said envelope and said conductors to force collection of electrons escaping from said gaps on said lead-in conductors and thereby to prevent electrons from bombarding the seals between said conductors and said envelope.

between said envelope and said conductors to force collection of electrons escaping from said gaps on said lead-in conductors and thereby to prevent electrons from bombarding the seals between said conductors and said envelope.

6. A magnetron device adapted to have high-power output comprising an envelope, a source of electrons, an anode structure within said envelope adjacent said source of electrons including a pair of mutually spaced anode members having opposed surfaces and defining between said surfaces a space charge chamber within which electrons constituting the space charge of the device are adapted to move, said anode members also defining between said surfaces gaps located on the periphery of said space charge chamber, lead-in conductors sealed through said envelope and connected with said anode members, and metallic shielding means surrounding each of said lead-in conductors and supported in insulated relation with respect thereto in the path of electrons traveling from said gaps to the region of the seals between said envelope and said conductors to force collection of electrons escaping from said gaps on said lead-in conductors and thereby to prevent electrons from bombarding the seals between said conductors and said envelope.

7. A magnetron device adapted to have high power output comprising an envelope, a source of electrons, an anode structure within said envelope adjacent said source of electrons including mutually spaced anode members having opposed surfaces and defining between said surfaces a space charge chamber within which electrons constituting the space charge of the device are adapted to move, said anode members also defining between said surfaces gaps located on the periphery of said space charge chamber, shielding means for minimizing the escape of electrons from said gaps including a pair of angular members of conducting material substantially completely covering each of said gaps, each of said angular members in each said pair being supported from a different one of said anode members and having a portion extending toward the other of said angular members in overlapping relationship therewith over one of said gaps whereby said angular members cooperate with the anode structure to collect electrons passing through said one of said gaps.

8. A magnetron device adapted to have high power output comprising an envelope, a source of electrons, an anode structure within said envelope adjacent said source of electrons including a pair of mutually spaced anode members having opposed surfaces and defining between said surfaces a cylindrical space charge chamber within which electrons constituting the space charge of the device are adapted to move, said anode members also defining between said surfaces gaps located on diametrically opposite sides of said cylindrical space charge chamber, shielding means for minimizing the escape of electrons from said gaps including a pair of L-shaped members of conducting material substantially completely covering each of said gaps, each of said L-shaped members in each said pair being supported from a different one of said anode members by one arm and having the other arm extending toward the other of said L-shaped members in overlapping relationship with the other arm thereof over one of said gaps whereby said L-shaped members cooperate with the anode structure to collect electrons passing through said one of said gaps.

9. A magnetron device adapted to have high power output comprising an envelope, a source of electrons, an anode structure within said envelope adjacent said source of electrons including mutually spaced anode members having opposed surfaces and defining between said surfaces a space charge chamber within which electrons constituting the space charge of the device are adapted to move, said anode members also defining between said surfaces gaps located on the periphery of said space charge chamber, means for minimizing the escape of electrons from said gaps including a pair of shield members of conducting material substantially completely covering each of said gaps, each of said shield members in each said pair being supported from a different one of said anode members and having a portion extending toward the other of said shield members in overlapping relationship therewith over one of said gaps whereby said shield members cooperate with the anode structure to collect electrons passing through said one of said gaps.

10. A magnetron device adapted to have high power output comprising an envelope, a source of electrons, an anode structure within said envelope adjacent said source of electrons including mutually spaced anode members having opposed surfaces and defining between said surfaces a space charge chamber within which electrons constituting the space charge of the device are adapted to move, said anode members also defining between said surfaces gaps located on the periphery of said space charge chamber, lead-in conductors sealed through said envelope and connected with said anode members, and means in the path of electrons traveling from said gaps to the region of the seals between said envelope and said conductor for forcing collection of electrons escaping from said gaps on said conductors comprising an insulating cylinder secured to and surrounding each said conductor between said envelope and said anode members, and an apertured metallic disk surrounding each said conductor and supported from each said cylinder in insulated relationship to said conductor.

11. A magnetron device adapted to have high power output comprising an envelope, a source of electrons, an anode structure within said envelope adjacent said source of electrons including mutually spaced anode members having opposed surfaces and defining between said surfaces a cylindrical space charge chamber within which electrons constituting the space charge of the device are adapted to move, said anode members also defining between said surfaces gaps located on the periphery of said space charge chamber, parallel lead-in conductors sealed through said envelope by glass to metal seals and terminating in said anode members, and means in the path of electrons traveling from said gaps to the region of the seals between said envelope and said conductor for forcing collection of electrons escaping from said gaps on said conductors comprising an insulating cylinder secured to and surrounding each said conductor between said envelope and said anode members, and an apertured metallic disk surrounding each said conductor and supported from each said cylinder in insulated relationship to said conductor.

12. A magnetron device adapted to have high power output comprising an envelope, a source of electrons, an anode structure within said en-

velope adjacent said source of electrons including mutually spaced anode members having opposed surfaces and defining between said surfaces a space charge chamber within which electrons constituting the space charge of the device are adapted to move, and a shielding structure supported in insulated relation with respect to said anode structure for preventing electrons escaping from said space charge chamber from bombarding said envelope, said shielding structure comprising a hollow metallic enclosure substantially totally enclosing the portions of said anode structure defining said space charge chamber.

13. A magnetron device adapted to have high power output comprising an envelope, a source of electrons, an anode structure within said envelope adjacent said source of electrons including mutually spaced anode members having opposed surfaces and defining between said surfaces a space charge chamber within which electrons constituting the space charge of the device are adapted to move, said anode members also defining between said surfaces gaps located on the periphery of said space charge chamber, and a shielding structure supported in insulated relation with respect to said anode structure for preventing electrons escaping from said space charge chamber from bombarding said envelope, said shielding structure comprising a hollow metallic enclosure substantially totally enclosing the portions of said anode structure defining said space charge chamber.

14. A magnetron device adapted to have high power output comprising an envelope, a source of electrons, an anode structure within said envelope adjacent said source of electrons including mutually spaced anode members having
